COMPUTER OUTPUT MICROFILMER

Maurice H. Artaud, Spring Valley, Calif., assignor to
Stromberg-DatagraphiX, Inc., San Diego, Calif.

Filed May 23, 1974, Ser. No. 472,573

Term of patent 14 years

Int. Cl. D16—03

U.S. Cl. D61—1 Q

FIG. 1

FIG. 2

FIG. 3

FIG. 1 is a front perspective view of a computer output microfilmer showing my new design;

FIG. 2 is a top plan view thereof; and

FIG. 3 is a rear perspective view thereof.

I claim:

The ornamental design for a computer output microfilmer, as shown.
